(57) CLAIM

The ornamental design for a fragrance bottle and cap, substantially as shown and described.

DESCRIPTION

FIG. 1 is a top, front and right side perspective view of a first embodiment of a fragrance bottle and cap showing our new design;

FIG. 2 is a top plan view thereof;

FIG. 3 is a front elevation view thereof, the rear elevation view being a mirror image thereof;

FIG. 4 is a side elevation view thereof, the opposite side elevation view being a mirror image thereof;

FIG. 5 is a bottom plan view thereof;

FIG. 6 is a top, front and right side perspective view of a second embodiment of a fragrance bottle and cap showing our new design;

FIG. 7 is a top plan view thereof;

FIG. 8 is a front elevation view thereof, the rear elevation view being a mirror image thereof;

FIG. 9 is a side elevation view thereof, the opposite side elevation view being a mirror image thereof; and,

FIG. 10 is a bottom plan view thereof.

In the drawings, the broken lines in FIGS. 5 and 10 depict portions of the design that form no part of the claim.

1 Claim, 4 Drawing Sheets
